UNITED STATES PATENT OFFICE.

ERNST F. STECK, OF CHICAGO, ILLINOIS.

WATER-TOWER.

SPECIFICATION forming part of Letters Patent No. 527,460, dated October 16, 1894.

Application filed November 22, 1893. Serial No. 491,620. (No model.)

To all whom it may concern:

Be it known that I, ERNST F. STECK, a citizen of the United States, residing at Chicago, in the county of Cook and State of Illinois, 5 have invented certain new and useful Improvements in Water-Towers, of which the following is a full, clear, and exact specification.

My invention relates to improvements in 10 portable water towers of the class ordinarily employed in extinguishing fires.

One of the objects of my invention, is to be able to incline the stand pipe in the direction of the discharge from the nozzle, and to alter 15 the direction of such inclination of said pipe simultaneously with any change in the direction of discharge; whereby the recoil of the discharge will at all times be counteracted or resisted whatever be the direction of such 20 discharge.

A further object of my invention is to so dispose and arrange the tower frame and its stand pipe with reference to the turn-table hereinafter described, that the center of gravity 25 of such frame and pipe will fall more nearly over the center of the turn-table than heretofore, when the said tower-frame and pipe are inclined; whereby the liability to capsize will be reduced to a minimum.

30 A still further object of my invention is to get the point of connection between the base of the tower and the carriage or truck nearer to the ground than heretofore, so that when the tower-frame and stand pipe are in their lowered positions the whole base of the frame 35 will be below the frame of the truck and will rest between and be securely held against side flection by the side members of the truck frame, and whereby also the apparatus may 40 be shifted from place to place at the scene of action without danger of capsizing while the tower-frame and stand-pipe are erect.

45 My invention consists in certain features of novelty by which the said objects and certain other objects hereinafter described are attained, as fully explained with reference to the accompanying drawings, and more particularly pointed out in the claims.

50 In the said drawings, Figure 1 is a side elevation of my improved tower and its truck

or carriage, the upper part of the tower being broken away, and Fig. 1^a is a side view of such upper portion. Fig. 2 is a side elevation of a portion of the lower end of the tower and the truck on a larger scale, showing the 55 tower erect. Fig. 3 is a longitudinal section taken on the line 3—3, Fig. 4, of the box at the upper end of the tower-frame showing a part of the stand-pipe therein. Fig. 4 is a transverse section of the same taken on the 60 line 4—4, Fig. 3. Fig. 5 is a plan section taken on the line 5—5, Fig. 2. Fig. 6 is a detail transverse sectional view of the turn-table (hereinafter described) and carriage frame taken on the line 6—6, Fig. 5, drawn 65 to a larger scale, and Fig. 7 is a transverse sectional view of the truck frame taken on the line 7—7 Fig. 5, looking in the direction of the arrows.

In carrying out my invention I provide the 70 side members 1 of the truck or carriage frame with a counter-sink or drop 2 which is formed between the front and rear wheels of the truck preferably forward of the center or mid-length of the frame and as near to the front 75 wheels as possible without getting over the axle or other part of the running gear, so that the space below the counter-sink will be entirely unobstructed, to permit of the free movement of the hose, and at the same time 80 the tower frame whose base is situated in this counter-sink as hereinafter described, will over-lie a maximum portion of the length of the truck when in its lowered position. Mounted upon the truck frame in this coun- 85 ter-sunk portion 2 is a turn-table 3 which pref- erably consists of a cog ring 4 secured to a similar ring 5 whose inner edge is beveled and engages under a beveled ring 6 secured to the portions 2 of the truck frame by suit- 90 able brackets or angle irons 7 as shown in Fig. 6. This cog ring is engaged by pinions 8 journaled in boxes 9 secured to one of the cross members 10 on each side of the truck. The lower end of the shaft of each of the pin- 95 ions 8 is provided with a beveled gear 11 which engages with a similar gear 12 mounted on the inner end of a turning stem 13 journaled in the side portion 2 of the truck frame and being adapted for the application of any 100

suitable crank (not shown) whereby the turn-table may be revolved from either side of the apparatus.

The tower proper consists of a hinged or pivoted frame and an extensible stand-pipe arranged therein as hereinafter described. The said tower frame is designated by the numeral 14, and is hinged or pivoted at its base by means of short standards 15 to the turn-table, and when in its lowered position as shown in Fig. 1, it rests between the rear portions of the frame 1, or more accurately speaking, between the running boards or seats 16 which extend along the inner edges of the truck frame with a space between them for the reception of the tower-frame, the cross member 17 of the truck frame, upon which the forward ends of the boards 16 are supported, being curved downwardly between the boards 16 so as not to obstruct the descent of the tower frame. By this arrangement and construction I am enabled to get the turn-table and base of the tower very near to the ground and at the same time have the tower frame 14 nearer the horizontal when in its lowered position, than heretofore; and I attain a further advantage in that the tower frame while resting between the boards 16 during the run, is securely braced and held against side flexion, and the hinge or pivot of the tower frame and its other connections thus spared the severe strain which they might otherwise receive from this cause.

Arranged within the tower frame 14 is the extensible stand-pipe 18 to whose lower end may be secured the hose 19 which is ordinarily carried in a basket 20 under the truck and is adapted to be drawn up through the tower frame by the stand-pipe as the latter rises therefrom. Near the upper end of the frame 14 is journaled a sheave 21 and at its lower end a drum 22; and 23 is a cable which passes over the sheave and takes one or more turns around the drum and has both ends secured to the stand-pipe by means of a suitable lug 24 arranged at or near the base thereof. The inner sides of the peripheries of the said drum and sheave are so disposed with reference to the lug 24 that they will be substantially in a straight line with the point of attachment between the cable and lug, whereby the pull will be substantially parallel with the stand-pipe, and the base of the latter thus held away from the sides of the frame when being extended or withdrawn. A further advantage in connecting both ends of the cable to the stand-pipe is that the latter may be withdrawn while at an angle, without depending upon the force of gravity for causing it to recede into the frame. The drum 22 may be provided with suitable gear connection with ratchet wheel 25 having a winding stem 26 for the application of a hand crank.

As a means for erecting and lowering the tower proper, I employ a pair of screw rods

27 which engage in boxes or nuts 28 swiveled to the sides of the frame 14, while the lower ends of such rods are rotatably held in boxes 29 pivoted to the turn-table on the opposite side thereof to that on which the tower-frame is hinged. These screw rods 27 may be actuated simultaneously by means of a suitable hand crank applied to either of two winding stems 30 on the extremities of a horizontal shaft 31 journaled in suitable bearings on the turn-table, the shaft 31 being provided with miter-gear connection 32 with each of the screw rods; and in order that such screw rods may be simultaneously actuated and the angle of inclination of the tower varied when the table is turned so as to render the stems 30 inaccessible, I provide the shaft 31 at an intermediate point with miter-gear connection 33 with a supplemental winding stem 34 journaled in a box 35 on the turn-table about mid-way between the stems 30.

The upper extremity of the stand-pipe 18 is provided with a discharge nozzle 36 which may be of the usual form having a flexible connection 37 with the said pipe and being provided with a controlling cord 38 extending to a point of convenience at the base of the tower frame. The elevation of this nozzle however is restricted to an upright plane by means of the side plates 39 each having a slot 40 in which a pin on a part of the nozzle plays. In this manner the nozzle is fixed with reference to the stand-pipe, save for the movement permitted by the slots 40. The stand-pipe itself is fixed against rotation independently of the turn-table in any suitable way, but preferably by means of a spline or feather 41 formed along the pipe and working in grooves 42 formed in one roller 43—44 respectively of each of two series of rollers 45—46 journaled in a box-like portion 47 of the tower-frame 14 on the upper end thereof. There are preferably four rollers in each of these series, having peripheries complementary in shape to and fitted snugly against the pipe 18, and the two series are arranged at such distance apart as to hold the pipe firmly, and prevent it from jostling the sides of the tower-frame, the lower end of the pipe being supported by a bracket 48 when in its retracted and reclined position. It will thus be seen that the lateral discharging direction of the nozzle is controlled or changed entirely by the bodily rotation of the turn-table, and that such discharging direction of the nozzle never changes but is fixed with relation to the turn-table, and is always in a direction away from the side of the table to that on which the tower-frame is hinged, and lengthwise of the lifting rods 27. Hence the strain resulting from the recoil of the discharge, which when multiplied by the great leverage afforded by the tall stand-pipe, is very great, is invariably brought lengthwise of the lifting rods and transversely of the axis of the hinge; and serious strain to these parts

thereby avoided; and a further important advantage of this fixed relation between the nozzle and the turn-table, is that no matter in what direction the nozzle is turned, the rotation of the screw rods 27 in the proper direction, will invariably tilt the tower in the same direction as the nozzle discharges, and thus resist the recoil and prevent the capsizing of the apparatus if its position be such that the force of the recoil destroys its equilibrium which is often the case when directing the stream from the side of the apparatus while standing on sloping or irregular ground. Furthermore such fixed relation between the nozzle and table, combined with the hinged tower causes the direction of inclination of the tower to simultaneously change with any change however sudden in the direction of the discharge, and thus avoid the necessity of shutting off the water from the stand-pipe or else running the risk of capsizing the apparatus while the nozzle and inclination of the tower are being adjusted to another position.

25 The tower-frame is hinged to the turn-table at its extreme outer edge as shown, in order that the center of gravity thereof may be brought more nearly over the center of the turn-table when the tower is inclined for the purpose of getting the nozzle in a more advantageous position or for other reasons; and in order that this eccentric relation of the tower-frame to the turn-table may exist without causing any interference from the hose, 30 to the free rotation of the turn-table, the latter is open in its center beneath the stand-pipe as shown in Fig. 5, so that the hose may pass through, and the cross members 10 of the truck-frame are curved outwardly as indicated in Figs. 6 and 7 and as appears in Fig. 5, so that the space below the turn-table in the path of the hose will be unobstructed and such hose permitted, if necessary, to describe a complete circle when the turn-table 35 is rotated.

Having thus described my invention, what I claim as new therein, and desire to secure by Letters Patent, is—

1. The combination with a carriage and a turn-table mounted thereon and having means for turning it, of a tower frame hinged to said turn-table at its outer edge, rods for bracing and lifting said frame, mounted on said turn-table and engaging with said frame, 50 an extensible pipe mounted in said frame and having a nozzle fixed with relation to and adapted to turn with said turn-table and being permanently confined to oscillate or bend in an upright plane extending transversely 55 of the hinge at the base of the tower frame and lengthwise of said brace and lifting rods; whereby the tower frame may be inclined in any direction to resist the recoil, and the strain resulting from the weight of the frame 60 and such recoil will invariably be exerted

lengthwise of said brace and lifting rods, substantially as set forth.

2. The combination with a turn-table and a tower frame hinged thereon and having means for raising it, of an extensible stand-pipe mounted in said frame and having a spline or feather, rollers mounted in said frame for holding and guiding said pipe, one of said rollers being provided with a groove for receiving said spline, and a nozzle fixed 75 on said pipe against independent rotation, substantially as set forth.

3. The combination with a turn-table and a tower frame hinged thereon, of an extensible stand-pipe arranged in said frame and 80 being provided with a spline or feather, two series of rollers mounted in said frame near the upper end thereof and having peripheries complementary in shape to and fitting against said pipe, a number of said rollers 85 being provided with grooves for the reception of said spline, and the two series being arranged at such a distance apart as to hold the pipe rigidly within the tower frame and away from the sides thereof, and a nozzle 90 fixed to said pipe against independent rotation, substantially as set forth.

4. The combination with the carriage and a turn-table having means for turning it, mounted on said carriage, of a tower frame 95 hinged to said turn-table at its outer edge or perimeter at a point remote from the center thereof, a stand-pipe in said frame, adapted to be attached to a hose and being fixed against independent rotation, a flexible nozzle on said stand-pipe fixed against independent rotation, means for erecting said tower frame, mounted upon the opposite side of said turn-table, said turn-table being open under the base of said stand-pipe, and the 100 space beneath the turn-table being unobstructed, whereby the hose depending from said stand-pipe may describe a complete circle when the turn-table is rotated, substantially as set forth.

5. The combination of the carriage frame having the cross-members 10 turned outwardly or away from each other, an annular turn-table mounted upon said frame and cross-members, and being open or unobstructed underneath, a tower frame hinged to said turn-table at its outer edge, a stand-pipe in said frame, adapted to be attached to a hose, means for raising said tower-frame, mounted upon the opposite side of said turn-table, said cross-members being turned outwardly or away from one another under the line of movement of the base of said stand-pipe, and the base of the stand-pipe being arranged directly over the opening under the 115 turn-table, whereby the hose may pass up through the turn-table and revolve with the stand-pipe without obstruction in its movement, substantially as set forth.

6. The combination with the truck, of a 120

turn-table mounted thereon and having a cog ring, a tower hinged to said turn-table, a shaft journaled on said turn-table and having winding stems projecting from both sides thereof, screw rods pivoted on said turn-table and being geared to said shaft and having connection with said tower, a supplemental winding stem journaled on said turn-table

intermediate of said first winding stems and being geared to said shaft and adapted to turn said screw rods simultaneously, substantially as set forth.
